UNITED STATES PATENT OFFICE.

FRITZ BALZER, OF MOLINE, ILLINOIS, ASSIGNOR TO TROY LAUNDRY MACHINERY CO., LTD., OF CHICAGO, ILLINOIS, A CORPORATION OF NEW YORK.

GARMENT PRESS.

Application filed October 20, 1924. Serial No. 744,612.

The present invention relates to garment presses.

Garment presses as heretofore manufactured and used have resulted in a number of accidents to operators. Various types of guards and controls have been devised for the purpose of minimizing the danger from accident, but such devices have left much to be desired. Though the present invention will be described in connection with garment presses its field of usefulness is much broader, the subject matter of the present invention being applicable to presses for a wide variety of purposes.

An object of the present invention is to provide a positively operated press in which the danger to the operator is reduced to a minimum.

A further object is to provide an improved power operated press having a guard for shielding the operator from the danger zone, which guard, while being effective to protect the operator, will not slow down the operation of the press.

A further object is to provide a safety press which is simple and certain in operation, which will protect the operator thereof and which will be convenient to use.

A further object is to provide a power operated press having combined guard and control means for effectively governing the operation of the machine and for protecting the operator from danger.

Further objects will appear as the description proceeds. Referring to the drawings—

Figure 1 is a view in side elevation of a garment press embodying the principles of the present invention;

Figure 2 is a view in front elevation of the structure shown in Figure 1;

Figure 3 is a fragmentary view illustrating certain of the parts when the upper pressing buck is in its upper or inoperative position;

Figure 4 is a view similar to Figure 3 but showing the parts as they are disposed when the upper buck is in its lower or operative position;

Figure 5 is a detailed view, partly in section, illustrating certain control mechanism;

Figure 6 is a fragmentary view illustrating certain control mechanism with the upper buck in its inoperative or nonpressing position;

Figure 7 is a view similar to Figure 6 but

showing the mechanism of Figure 6 in the position which it assumes when the upper buck is in its operative or pressing position; and

Figure 8 illustrates means for equalizing pressure on the various portions of the upper buck when garments of non-uniform thickness are being pressed.

Figure 9 illustrates certain coupling mechanism.

Referring first to Figures 1 and 2, the numeral 1 indicates a standard, which may have the three supporting legs 2, 3 and 4. Said standard forms a rigid support for the lower buck 5 and for the work table 6. Carried by the standard is the bracket 7, which provides a pivotal mounting for the lever 8, said lever 8 being swung about the axis indicated by the numeral 9. The lever 8 is provided at its upper portion with the two arms 10—10 each of which is provided with a pressure equalizer indicated by the numeral 11. Said pressure equalizers do not constitute the present invention and need not be described in detail herein. It may be stated briefly, however, that said pressure equalizers provide resilient mountings for the upper buck 12, whereby when the upper buck 12 is moved into pressing relationship with the lower buck 5 the two equalizers 11—11 may yield sufficiently to equalize the pressure when garments of non-uniform thickness are being pressed.

Mounted at the lower end of the lever 8 is the pitman 13, which pitman is connected to the crank 14. Said crank 14 is rigidly mounted upon the shaft 15, which shaft is driven by the worm wheel 16. Said worm wheel 16 is connected to be driven by the worm 17, which worm 17 is rigidly mounted upon the shaft 18. Said shaft 18 is rigidly connected to the clutch element 19, which is adapted to have cooperative relationship with the clutch element 20. Said clutch element 20, which preferably takes the form of a fly wheel, is driven by the motor 21, which may operate continually while the press is in operation. Any preferred switch mechanism may be provided for controlling the energization of the electric motor 21.

Also mounted to have swinging movement about the axis 9 is the guard 22, which is adapted to be disposed in position to guard the operator against ingress to the pressing region. Said guard 22 is also adapted to

have a position out of the way of the pressing region, whereby the garments may readily be inserted into and removed from the press. The inoperative positions of the 5 guard 22 and the upper buck 12 are shown in dotted lines in Figure 1.

Hingedly connected to the guard 22 on an axis 23 displaced from the axis 9 is the control rod 24, which control rod governs the 10 operativeness of the clutch elements 20 and 19 in a manner which will be described presently. As shown in Figures 1 and 6, a pair of levers 25 and 26 are provided pivoted about the axis 27, which axis is displaced from the axes 9 and 23. The levers 15 25 and 26 are connected, respectively, to the arms 28 and 29, which arms are rotatably mounted upon the shaft 30. Said arms 28 and 29 have clutch portions which are spaced 20 apart along the shaft 30. Also mounted upon the shaft 30 and splined thereto is the coupling member 31. Said coupling member is capable of longitudinal movement on the shaft 30 but, being splined to said shaft, 25 will communicate rotative movement to said shaft when said coupling member is rotated. Said coupling member 31 is controlled by the bell crank 32, which in turn is controlled by the control rod 24.

30 It will be clear that swinging movement of the lever 8 will result in rocking movement of the arms 28 and 29. If the coupling member 30 is connected to either of said arms 28 or 29, rocking movement will be 35 communicated to said coupling member, and due to the non-rotatable connection between the coupling member 31 and shaft 30, a rocking movement will be communicated to said shaft 30. Non-rotatably connected to the 40 shaft 18 is the yoke 33, which yoke is provided with a pair of diametrically opposed pins 34-34 adapted to control the clutch element 19, which, as explained hereinbefore, drives the worm 17 to communicate motion 45 through the worm wheel 16, crank arm 14 and pitman 13 to the operating lever 8 of the press. The clutch element 19 may be provided with a suitable groove for receiving the pins 34-34 of the yoke 33. Said 50 movable clutch element 19 may be urged into gripping relationship with the clutch element 20 by means of the spring 35, whereby an operative connection will be had between the motor 21 and the operating lever 55 8 at all times except when the clutch element 19 is positively held against the tension of the spring 35 out of clutching relationship with the clutch element 20.

Coupling member 31 has a lost motion connection with arm 28 when at one extremity of its axial movement and has a lost motion connection with arm 29 at the other extremity of its axial movement. When coupling member 31 is moved out of cooperative 65 relationship with one of the arms 28 or 29

it is moved into cooperative relationship with the other of said arms. Said arms 28 and 29 may have single projecting teeth adapted to engage with single projecting teeth of the coupling member 31, said teeth being disposed in such positions that arms 28 and 29 will actuate coupling member 31 to release clutch element 19 when the lever 8 is at or near the two extremities of its travel. Referring to Figure 9, the boss of 70 arm 28 is provided with a tooth 36 adapted to engage with a tooth 37 on the adjacent face of coupling member 31. The other face of coupling member 31 is provided with a tooth 38 adapted to engage with a tooth 39 on the boss of arm 29.

A mode of operation of the above described embodiment of the present invention is substantially as follows: When the operator desires to start work, he closes the circuit to energize the motor 21, whereby the clutch element 20 will rotate continuously. At this time the guard 22 and the upper buck 20 will be in their uppermost or inoperative positions, as indicated in dotted lines in Figure 1 and as shown in Figure 3. The means for heating the bucks 5 and 12 is not illustrated herein inasmuch as the heating features form no part of the present invention. At this time the levers 25 and 26 will be in 90 their lowermost positions, the coupling element 31 will be in locked engagement with the arm 28, which arm 28 is connected to the lever 25, and the yoke 33 will hold the clutch element 19 out of cooperative relationship 100 with the clutch element 20.

After the operator has arranged the garments on the lower buck 5, he will move the guard 22 into guarding relationship with the pressing region.

By reason of the fact that the control rod 24 is connected to the guard 22, said movement of guard 22 to guarding position will result in the movement upwardly of said control rod 24. This movement will rock the bell crank 32 about its axis and will result in the longitudinal movement of the coupling element 31, whereby to move said coupling element 31 out of cooperative relationship with the arm 28. This action will permit the spring 35 to move the clutch element 19 into cooperative relationship with the clutch element 20. The motor 21 will now drive the shaft 18, worm 17, worm wheel 16, crank 14 and pitman 13 to communicate swinging movement to the lever 8 in a clockwise direction, whereby the upper buck 12 will be positively moved into pressing relationship with the lower buck 5. As noted above, the universal connecting means 11-11 will compensate for any lack of uniformity of the garment being pressed. The longitudinal movement above referred to of the coupling element 31 out of cooperative relationship with the arm 28 will 125 130

bring the opposite face of the coupling element 31 into position to be engaged by the tooth of the arm 29. When the upper buck 12 has moved to its lowermost position, the 5 crank 14 and pitman 13 will be in line, or nearly so, as shown in Figures 1 and 4. Said crank 14 and pitman 13 form members of a toggle mechanism and will exert a powerful action upon the lever 8 whereby to exert a 10 heavy pressure in the pressing operation. The coupling element 31 and the arm 29 will be so designed that when the crank 14 and pitman 13 are approximately in a straight line, lever 26 will have moved arm 15 29 to such a position as to exert a rocking movement upon the coupling element 31, whereby to rock the yoke 33 to withdraw the clutch element 19 out of cooperative relationship with the clutch element 20. Communication 20 will, therefore, be interrupted between the motor 21 and the worm wheel 16. Inasmuch as the worm wheel 16 and worm 17 are non-reversible, the mechanism will be locked in pressing position. This 25 pressing position will be maintained as long as the guard 22 is in its lowermost or guarding position. In order that an operator may attend to several machines at once, said operator may lock the guard in its guarding 30 position. The movement of the coupling element 31 out of cooperative relationship with the arm 29 will position the coupling element 31 in cooperative relationship with the arm 28. When the operator desires to 35 have the upper buck 12 moved to its uppermost position he will cause the guard 22 to move out of guarding relationship with the pressing region. For this purpose the guard 22 will ordinarily be biased to its upper position by a weight or spring, not shown. Movement of the guard 22 to its upper position will result in the lowering of the control rod 24, which, acting through the bell crank 32, will shift the coupling element 31 40 out of cooperative relationship with the arm 29 into cooperative relationship with the arm 28. By reason of the fact that the coupling element 31 is released from the arm 29, the spring 35 will allow the coupler element 19 to engage the coupler element 20, whereby 45 the motor 21 may again drive the worm 17, worm wheel 16, crank 14 and pitman 13. The continued rotation of the worm wheel 16 will result in movement of the upper buck 50 from its lowermost or operative position to its inoperative or uppermost position. When said buck has reached its uppermost position the tooth 36 on arm 28 will engage the coupling element 31 to produce a rocking movement of shaft 30 and yoke 33 to move the coupler element 19 out of cooperative 55 relationship with coupler element 20. The parts will now be locked with the upper buck in its upper or inoperative position. 60 At the same time the guard will be held in

its upper position, so that access may be had to the garments which have been subjected to the pressing operation. It will be clear that when the upper buck is in either its upper position or the lower position, it will be securely locked by reason of the locking action between the worm wheel 16 and worm 17. 70

It will be apparent that the present invention provides a press in which danger 75 to the operator has been reduced to a minimum. No inconvenience to the operator is involved in the provision of the safety mechanism, inasmuch as when it is desired to insert garments into the press or remove 80 garments therefrom, said safety mechanism is well out of the way. After said garments have been placed in proper position only a single manual movement is required by the operator to set the parts in motion to positively and powerfully apply the upper buck in pressing relationship with the lower buck. 85

Though a preferred embodiment of the present invention has been described in detail, it will be understood that many modifications will occur to those skilled in the art. It is intended to cover all such modifications that fall within the scope of the appended claims. 90

I claim: 95

1. A garment press, comprising a movable buck, means for transmitting power to said buck, said power transmitting means including a worm and worm wheel, means responsive to said buck for controlling said power transmitting means, a guard, and means responsive to said guard for governing said controlling means. 100

2. A press, including a movable pressing member, power transmitting means for moving said pressing member, said power transmitting means including normally nonreversible transmitting mechanism, means responsive to the movement of said movable pressing member for controlling the operativeness of said transmitting means, a guard, and means responsive to said guard for governing said controlling means. 105

3. A press, including a relatively movable pressing member, toggle means for transmitting power to said pressing member, nonreversible transmitting mechanism for operating said toggle means, a source of power, means between said source and said nonreversible power transmitting means for controlling the connection therebetween, a guard for said movable pressing member, and means jointly responsive to the movement of said guard and said movable pressing member for governing said controlling means. 115

4. A garment press, comprising a stationary buck, a movable buck, a lever having resilient connection with said movable buck for transmitting power thereto, a guard 120

130

mounted for swinging movement about the axis of said lever, power transmitting mechanism including non-reversible gearing for communicating motion to said lever, a source 5 of power, a clutch between said source of power and said non-reversible gearing, and mechanism jointly responsive to said lever and to said guard for controlling said clutch.

5. A garment press, including a relatively 10 stationary buck, a movable buck, means for positively moving said movable buck into cooperative relationship with said stationary buck, said means including a toggle mechanism, a source of power, means including a 15 coupler for connecting said source to said toggle mechanism, coupler control means, means responsive to said first mentioned means for actuating said coupler control means, a guard for said press, and means responsive to said guard for governing said 20 coupler control means.

6. A garment press, comprising a relatively stationary buck, a relatively movable buck, a lever having a resilient connection 25 with said movable buck for operating said movable buck, toggle means for operating said lever, a worm and worm wheel for driving said toggle means, a motor for driving said worm and worm wheel, a clutch for 30 governing the driving relationship between said motor and said worm and worm wheel, means for operating said clutch, means connected with said lever for moving said op-

erating means, a guard for said bucks, and means responsive to said guard for controlling the operativeness of said moving means. 35

7. A garment press, including a stationary buck, a movable buck, means for forcing said movable buck into pressing relationship with said stationary buck and for moving said movable buck out of said pressing relationship, a source of power, coupler mechanism between said source of power and said forcing means, means for disconnecting said coupler mechanism near both extremities of 40 the stroke of said movable buck, a guard and means responsive to said guard and to said movable buck for governing said disconnecting means. 45

8. A garment press, including a stationary 50 buck, a movable buck, means for forcing said movable buck into pressing relationship with said stationary buck and for moving said movable buck out of said pressing relationship, a source of power, coupler mechanism 55 between said source of power and said forcing means, means for disconnecting said coupler mechanism near the extremities of the stroke of said movable buck, a guard, and means responsive to said guard and to said movable buck for governing said disconnecting means. 60

Signed at East Moline, Illinois, this 22nd day of September, 1924.

FRITZ BALZER.
